TYPESETTING APPARATUS

Filed May 26, 1923

Fig. 5.

Inventor
Charles Ashton Henry Bullock
By
B. Singer, Atty.

UNITED STATES PATENT OFFICE.

CHARLES ASHTON HENRY BULLOCK, OF LONDON, ENGLAND.

TYPESETTING APPARATUS.

Application filed May 26, 1923. Serial No. 641,734.

To all whom it may concern:

Be it known that I, CHARLES ASHTON HENRY BULLOCK, a subject of the King of Great Britain, and a resident of London, 5 England, have invented a certain new and useful Improvement in Typesetting Apparatus, of which the following is a specification.

This invention relates to type setting apparatus of the kind described in the specification of my prior application Ser. No. 539,536 and in particular to the type ejecting units therein employed.

In apparatus of the above type the type is 10 stored in stationary channels arranged at such an angle that the type gravitates to the lower ends of the channels at which ends are placed the type ejecting units. Each of these units operates to eject a single piece 15 of type by the depression of a key.

One of the objects of the present invention is to reduce friction between the piece of type to be abstracted and the rest of the type within the channel.

20 In practice it is found that the weight of a channel full of type makes the removal of a single piece from the lower end of the channel a difficult process. This defect is removed according to this invention by 25 raising the piece of type to be removed to a position where it is almost clear of the rest of the type in the channel such elevation of a piece of type taking place automatically after each removal of a previously raised 30 piece of type. The present invention consists broadly of a type ejecting unit for use in connection with a type setting apparatus having stationary channels wherein the type is stored in which the piece of type 35 to be abstracted remains stationary during the depression of a spring supported plunger which serves upon depression to lower one or more of the adjacent pieces of type which were raised during the previous operation of the plunger.

40 A type ejecting unit according to the preferred form of the invention comprises a spring supported plunger provided with a platform which moves with it and serves to 45 collect two or more pieces of type when depressed and raise the same to an elevated position when released, and means such as a fixed projection or platform for maintaining a single piece of type in such elevated position during each depression of the 50 plunger whereby the same is maintained in

a position from which it may be readily abstracted.

In order that the invention may be clearly understood an embodiment of the same will 60 now be described by aid of the accompanying drawings in which:—

Fig. 1 is a diagrammatic perspective view of a typesetting frame showing units according to this invention in position in the 65 type channel.

Fig. 2 is a fragmentary perspective to an enlarged scale of one of the channels and an ejecting unit in position therein.

Fig. 3 is a part sectional elevation of the 70 unit and channel showing two pieces of type in the elevated position and the plunger of the unit in its raised or normal position.

Fig. 4 is a similar view but showing the plunger of the unit depressed and a single 75 piece of type in position for abstraction.

Fig. 5 is an underside plan view of a portion of one of the channels showing the apertures for the units and the means for securing the sides of the channels to the 80 base.

The type-setting frame shown in Fig. 1 comprises a rectangular frame 1 which is supported at an angle by means of legs 2, the inside of the frame being composed of a 85 plurality of parallel channels 3 in which the units 4 according to this invention are detachably secured.

A type ejecting unit according to the form of the invention shown comprises a casing 90 5 which is adapted to project through a slot 6 in the bottom of the channel in which the type 7 is stored, a pair of side flanges 8 at its upper end serving to support the same by engagement with the top edges of the 95 sides of the channel. In this position the casing is secured by means of a nut 9 and a U washer or saddle 10 disposed beneath the bottom of the channel. A spring supported plunger 11 is slidably mounted in this casing 100 and such plunger is formed with a platform or lateral projection 12 which extends through a slot 13 in the side of the casing which opposes the type in the channel. The upper edge of this platform is above the 105 bottom of the channel when the plunger is in its normal position.

When the plunger is depressed however this upper edge sinks to a position flush with or slightly below the bottom of the 110 channel in which position the adjacent pieces of type move thereover under gravity so

that when the plunger is released such pieces of type resting on the platform are raised with the plunger.

- 5 The side of the casing which opposes the type is formed with one or a pair of projections or ledges 14 the upper surfaces of which are flat and reside flush with or slightly below the normal level of the top edge of the aforesaid platform on the plunger.
- 10 These lips are of such a size as to engage a single piece of type only upon each depression of the plunger thus serving to hold such piece of type stationary when the plunger is depressed.
- 15 The upper end of the plunger is provided with a key or finger piece 15 having an opening 16 therein through which the single supported piece of type projects when the plunger is depressed. This piece of type
- 20 may thus be grasped by the operator's

fingers simultaneously with the depression of the plunger which is effected by the same medium.

What I claim and desire to secure by Letters Patent is:—

25 A type ejecting unit for use in connection with a type setting apparatus having stationary channels comprising a spring supported plunger provided with a platform which moves with it and serves to collect more than one piece of type when depressed and raise the same to an elevated position when released and means such as a fixed projection for maintaining a single piece of type in such elevated position during each depression of the plunger whereby the same is maintained in a position from which it may be readily abstracted.

30 In witness whereof I affix my signature.

CHARLES ASHTON HENRY BULLOCK.
